ERASURE SHIELD

**Grace D. Preston, Washington, D. C., assignor to
Paul S. Devine**

Application December 5, 1949, Serial No. 131,192

1 Claim. (Cl. 120—41)

1

The invention relates to erasure shields particularly adapted for erasing carbon copy sheets in a typewriter, and has for its object to provide a device of this kind wherein the shield is formed from a flexible paper folded to a shape whereby a trough is formed, V-shaped in cross section when the shield is inserted between a carbon sheet and the second sheet to catch the erasure particles, preventing them from accumulating between the sheets and forming blind spots, etc., as the typing continues, after an erasing operation.

A further object is to provide the lower part of the shield with a longer fold than the intermediate portion, thereby forming a thin edge, which edge can be forced between the sheets of paper in the typewriter, and the upper section moved upwardly to the desired line for erasing, thereby opening the trough. The lower flange also forms means whereby the shield can be longitudinally moved or slid between the sheets to the desired position.

A further object is to provide an erasure shield of the trough type comprising an apertured section, the apertures being adapted to register with an erasure point, a lower flanged guide and supported section adapted to be frictionally held between sheets, and an intermediate section forming a V-shaped trough when the shield is in use; said sections being foldable onto each other.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

Figure 1 is a perspective view of the erasure shield.

Figure 2 is a perspective view of the erasure shield, showing the shield in position between sheets of paper on a typewriter roller.

Figure 3 is a perspective view of the shield showing the shield in flat form.

Figure 4 is an end view of a typewriter roller with sheets extending partially around the roller and between the roller and pressure rollers, and the upper part of the shield moved to an erasing position.

Referring to the drawing, the numeral 1 designates a conventional form of typewriter roller, and 2 pressure rollers usually carried by a bottom guide shield 3, for guiding the paper around

the roller. Extending around the roller, for purposes of illustration, are sheets of paper *p* and carbon sheets *c*. The erasure shield 4 comprises an apertured section 5, an intermediate section 6 and a lower section 7 of greater length than the section 6. It will be noted that these sections, when bent upon themselves at 8, assume the shield form shown in Figure 1, and being formed from a stiff and flexible paper, will assume the positions and shapes shown in Figures 2 and 4. After an erasing operation the shield is opened and the particles collected can be easily brushed from the shield.

The section 7 is slightly longer than the section 6, therefore it will be seen that when the operator grasps the trough edge 9, and forces the section 7 downwardly between the sheets, a comparatively thin edge is presented below the shield as at 10, which thin edge will be friction-

shield, as at 10, which thin edge will be frictionally gripped between the sheets, and the operator can then slide the shield to the desired position and then move the apertured section 5 upwardly to the erasure point until the proper aperture 5a registers with the proposed erasure.

25 During this operation the V-shaped trough which catches the erasure particles is opened, indicated at 11. Therefore there is no danger of the particles clinging to the adjacent carbon sheets or between the sheets. After the erasing operation, the operator grasps the shield 9 between the fingers, removes the shield and shakes the residue therefrom. The shield does not grip and compact the residue, hence the residue to the surface of the paper from which the shield is made, hence will easily shake therefrom after the erasing operation.

From the above it will be seen that an erasure shield is provided which is simple in construction, and one wherein an anchoring flange is provided at its lower end, which flange will guide the shield as it is slid to an erasing position. It will also be seen that the trough can be opened to the desired width upon a slight rotation of the roller.

45 The invention having been set forth what is claimed as new and useful is:

claimed as new and useful is:

An erasure shield formed from flexible material and comprising an apertured erasure section arching the roll in engagement with the paper, the lower end of the erasure section terminating in an upwardly opening and forwardly extending trough forming section, the upper end of the trough forming section terminating in a downwardly extending section, said downwardly extending section terminating below the

lower end of the trough forming section and adapted to be gripped between the sheets of paper.

GRACE D. PRESTON.
